UNITED STATES PATENT OFFICE.

HARRY B. NEWTON, OF ROCKFORD, ILLINOIS, ASSIGNOR TO ROCKFORD MACHINE TOOL COMPANY, OF ROCKFORD, ILLINOIS, A CORPORATION OF ILLINOIS.

TOOL-FEED MECHANISM.

Application filed December 8, 1923. Serial No. 679,488.

This invention relates to tool-feed mechanism of the kind adapted for machine tools in which it is desired to advance a tool slide or a tool-carrying head with respect to the work in short step-by-step feed movements and in rapid traverse movements. My invention, in its present embodiment, is particularly designed for use on a planer.

10 The primary object is to provide a simplified and improved tool-feed mechanism adapted to be applied to horizontal, vertical or angular feed tools for transmitting either step-by-step feed or rapid traverse movement thereto.

Another object is to provide novel means for varying the step-by-step feed movement so that the tool or tools as the case may be, will be advanced for heavier or lighter 20 cuts, according to the nature of the work at hand.

Still another object resides in the provision of feed mechanism of the character referred to in which the feed movement is 25 derived from uniform reciprocation of an operating part and the variable speed is obtained through the agency of a novel lost-motion mechanism, including an adjustable part adapted to be set by the operator for 30 producing the several feed movements, which differ as to duration and consequently as to the distance the tool is advanced.

I have also aimed to incorporate with the feed mechanism, means for transmitting 35 rapid traverse movement to the tool or tools; and to provide a simple control whereby either the feed or rapid traverse connections may be established at will.

A further object is to provide a feed 40 mechanism of the character described which will be thoroughly practical and which may be manufactured at a comparatively low cost.

Other objects and attendant advantages 45 will be appreciated by those skilled in this art as the invention becomes better understood by reference to the following description when considered in connection with the accompanying drawings, in which—

50 Figure 1 is a front end elevation of a planer equipped with tool-feed mechanism embodying my invention;

Fig. 2 is a vertical sectional view transversely of the planer, along the drive shaft 55 at the top thereof;

Fig. 3 is an enlarged fragmentary side view of the feed mechanism;

Fig. 4 is a horizontal section taken substantially on the line 4—4 of Fig. 3;

Fig. 5 is a vertical section taken on the 60 line 5—5 of Fig. 4;

Fig. 6 is a detail section taken on the line 6—6 of Fig. 3;

Fig. 7 is a section taken on the line 7—7 of Fig. 6; and

Fig. 8 is a detail view showing the graduations for reference in setting the mechanism for feed movements of different length.

Referring more particularly to the drawings, it will be observed that I have for 70 purpose of illustration embodied my invention in a planer, but that only such parts of the planer are shown as are necessary for an understanding of the present invention. It will also be noted that the feed mechanism is applied to the tool-carrying head on the cross-rail; but it will be manifest as the invention becomes better understood, that said mechanism may be applied to either one or more tool slides or tool-carrying heads, whether mounted on the cross-rail or on the side columns, or in any other position. Furthermore, my invention is not limited to this particular type of machine 80 tool, but is generally applicable wherever 85 similar feed movements are desired.

The planer, shown briefly in Fig. 1, is of a conventional design, comprising an elongated bed 11, a work table 12 mounted to reciprocate on the bed, a horizontal cross-rail 13 above the table for vertical adjustment on ways 14 on side columns 15 which are rigidly joined at their upper ends by a top plate 16, and tool-carrying heads designated generally by 17, mounted for horizontal adjustment on ways 18 on the cross rail. Said heads are adapted to be traversed horizontally by means of feed screws 19 and 21 held against lengthwise translation with respect to the cross-rail and 90 threadingly engaged in their respective tool heads. Each of the heads 17 and 17' is adapted for carrying one or more tools (not shown) for planing work on the table when the latter is reciprocated by mechanism, not 100 shown, but which is well understood in this art.

The feed screws are adapted to be turned either by hand or by power for traversing the tool heads on the cross rail, the present 110

invention having reference to the power-operated means for turning said feed screws. Part of the power-operated mechanism for this purpose is, however, well known in the prior art and will be first briefly described.

Suitable mechanism is employed for reciprocating a feed-transmitting member, at present in the form of a rack 22, in timed relation with the reciprocation of the work-table. This mechanism comprises a driving gear 23 which revolves in a counter-clockwise direction viewing Fig. 3, when the table moves in the cutting stroke, and in a clockwise direction in the return stroke. This gear drives a friction head 24 through the agency of an intermediate gear 25; and said head is adapted to be intermittently engaged by a friction ring 26 for oscillating a housing 27, to which is attached a wrist pin 28 operating through connecting links 29 and 31 for reciprocating the rack 22. The ring 26 normally grips the head 24 in driving connection and is adapted to be released therefrom in an expanding action transmitted by an expander 32. This expander is adapted to travel between opposed stops 33 and 34 by rotative movement of head 24, and is adapted to be arrested by said stops and tilted thereby for expanding the ring 26. For example, the driving gear 23 revolves in a clockwise direction and the head 24, and consequently the friction ring 26, will be revolved in a counter-clockwise direction from the position shown in full lines in Fig. 3, until the expander 32 strikes the stop 34 and releases the friction ring from said head. During this rotative movement, about 180 degrees, the connecting links 29 and 31 which are connected together at one end by a radius link 35, will move the rack 22 downwardly a fixed distance, as will be obvious. When the gear 23 is reversed with reversal of the work-table, the friction ring will be moved in a clockwise direction until stopped by the expander 32 striking the stop 33, thereby imparting an upward stroke to the rack 22. It will be manifest that each stroke of the rack will be uniform as to the extent of its travel and that the rack is reciprocated in timed relation with the work-table. The foregoing mechanism is known in the prior art; and my present invention, while utilizing such mechanism or the equivalent, has more particular reference to mechanism operated by the rack 22 for transmitting feed movement to either or both of the feed screws 19 and 21 for traversing their respective tool heads in either direction.

Referring more particularly to Figs. 3 and 4, it will be seen that in one end of the rail 13, I have mounted for rotation a pinion 36 in mesh with the rack 22 and having dental clutch teeth 37 in one end. A feed shaft 38 concentric with the pinion 36 and

journaled at 39 and 41 in the rail and said pinion respectively, is adapted to be connected to said pinion through the agency of a shiftable clutch element 42 having clutch teeth 43 complementary to the teeth 37. Said clutch element 42 is adapted to be shifted by means of a shifter arm 44 fixed to a shaft 45 journaled in a bracket which will be described hereinafter, to which shaft is attached a control lever 46. The shaft 38 and pinion 36 are held by suitable end thrust collars or surfaces against endwise displacement in their respective bearings. The shaft 38 extends at one end beyond the end of the cross-rail and carries on said extended end a loose feed gear 47, fixed disk 48 and a loose disk 49, both the gear 47 and disk 49 being recessed for the reception of the disk 48, as shown plainly in Fig. 4. A split friction ring 51 embracing and frictionally engaging a hub on the gear 47 and held against rotation by connection with the rail 13, serves to hold the gear 47 against rotation by reason of frictional contact with adjoining parts, except when positively moved as will be presently described. The disk 48 has a peripheral projection or lug 52 adapted to strike a projecting part 53 on the gear 47 for transmitting rotative movement in counter-clockwise direction viewing Fig. 3, from said disk to said gear. Rotative movement in the opposite direction is transmitted from said disk to the gear through the agency of the disk 49 which is adjustably connected to the disk 48 by means of a plunger 54, and which has a projecting part 55 on the side of the part 53 opposite from the projection 52. Said plunger 54, normally held in said connected position by means of a spring 56 is adapted to be withdrawn by grasping its knurled end 57, and upon rotative movement of the disk 49 with respect to the disk 48 is adapted to be engaged in any of the holes 58 in the latter disk. This adjustment obviously positions the projecting part 55 at greater or less distance from the projection 52, which consequently allows a corresponding lost motion in the movement transmitted by the disks to the gear 47. The purpose of this construction is, therefore, to transmit variable movement from the feed shaft 38 to the feed gear 47. As the parts are shown in full lines, a substantially direct connection is established between the disks and the feed gear, thus oscillating said gear a maximum number of degrees in each direction. By setting the plunger 54 in any of the holes between its present position and the projection 52, the projecting part 55 will be moved or positioned a corresponding distance from said projection 52, thereby decreasing the rotative movement imparted to the feed gear the amount of the lost motion between the disks and the feed gear. The number and

spacing of the holes 58 are not important, as any suitable means may be employed for connecting the two disks so that one may be rotarily adjusted with respect to the other. In the present instance, graduations are provided for indicating the extent of the adjustment; and by reference to Fig. 8, it will be observed that the disk 49 has a pointer which co-operates with graduations 10 on a collar 59 fixed to the shaft 38.

The gear 47 transmits feed movement to either one or both of the feed screws through mechanism which will now be described. Said gear 47 meshes with a gear 61 suitably 5 journaled on the cross-rail, and this gear 61 meshes with gears 62 and 63 loosely revolvable on the feed screws 19 and 21, respectively. Each of the gears 61, 62 and 63 is provided with a ratchet device well known 20 in this art for connecting it to its respective supporting shaft for transmitting rotary motion thereto in either direction. The construction of said ratchet devices being similar, a description of one will suffice. A 25 collar 64 fixed to the supporting shaft or feed screw 19, carries a pivoted pawl having diametrically opposed teeth 65 and 66, adapted to be turned by a handle 67 to bring either tooth into operative relation with the 30 internal teeth 68 in the gear 62. As the pawl is shown in Figs. 3 and 7, the gear 62 imparts rotative movement to the feed screw 19 only when revolved in a counter-clockwise direction. It follows that upon movement 35 of the feed gear 47 in a clockwise direction viewing Fig. 3, it will with the parts as shown, transmit feed movement to the feed screw 19 in a counter-clockwise direction, and that upon the reverse oscillation of 40 said feed gear the gear 62 will ride idly over the ratchet 65. Suitable means is provided for yieldingly holding the pawl in either of its set positions, as is well understood in this art. Thus it will be seen that by setting the 45 pawl so as to bring either of its teeth 65 or 66 into operative relation with the gear or driving element 67, the feed screw 19 may be turned in either direction in step-by-step movements by the feed mechanism just described.

I have also provided mechanism co-operating with the feed mechanism for transmitting rapid traverse movement to the gear 47 and consequently to the feed screws, 55 which will now be described. At the side of the machine adjoining said feed mechanism, I have provided a vertical rapid traverse shaft 69 held against axial translation, and in this instance continuously driven 60 from its upper end either forward or reverse, by any suitable means. As shown in Figs. 1 and 2, said rapid traverse shaft is connected by bevel gears 71, to a horizontal shaft 72, in turn adapted to be driven from 65 a pulley 73 through the agency of reversing

gears 74 and 75, these gears being loose on the shaft 72 and the gear 74 being fixed with respect to the pulley 73. By means of a shiftable clutch element 76 adapted to be shifted by operation of a hand lever 77, either gear 74 or 75 (which revolve in opposite directions) may be connected to the shaft 72 for driving the rapid traverse shaft forward or reverse. I have provided gearing operable between the shaft 69 and the 75 gear 47 for driving the latter gear at a speed considerably faster than the feed speed for rapidly traversing the tool head or heads on the cross-rail. This gearing includes a clutch adapted to be shifted by means of 80 the hand lever 46 described above. Said gearing comprises a spur gear 78, Fig. 3, concentric with the shaft 69 and journaled in a bracket 81 having a vertical portion 82 bolted to the adjacent end of the cross-rail. 85 The gear 78 is adapted to be connected to the shaft 69 by means of a clutch element 83 splined on said shaft and shiftable by the control lever 46. This lever, supported on the bracket 81, for connecting the rapid 90 traverse shaft 69 to the gear 78, when shifted downwardly connects the pinion 36 to the feed shaft 38, as above mentioned. The gear 78 meshes with a gear 84 journaled in the bracket 81 and having formed integral there- 95 with a bevel gear 85 which meshes with a complementary gear 86 fixed to a shaft 87 which is in driving connection with the feed gear 47 through the pinion 88. The screw passing through the gear 85 forms no part 100 of the present invention.

When the machine is in operation, the rack 22 is being reciprocated in a uniform stroke. The rapid traverse shaft may remain idle or may be driven in either direction according to the will of the operator, as determined by the position of the lever 77. The operator may engage either the feed or rapid traverse driving mechanism by operation of the control lever 46. This 105 will transmit rotative movement to the gear 47 either in oscillatory feed movements or in continuous rotary movements in either direction according to which clutch is engaged by said control lever 46 and accord- 110 ing to the position of the lever 77. Such rotative movement of the gear 47 will be transmitted to either one or both of the feed screws 19 and 21 according to the position 115 of their respective ratchet devices. The duration of the feed movement will be determined by the position of the plunger 54 on the disk 48, as explained above. The setting of the plunger 54 for different lengths 120 of feed may be quickly and easily done; and this variable feed mechanism is especially conducive to simplicity in the construction and operation of this type of feed mechanism. It is believed that the purpose of the feed and rapid traverse movements are well 125 130

understood by those skilled in this art, and that description in that direction is unnecessary. It should be noted, however, that my improvements are not necessarily limited to the combination shown herein, that is, in conjunction with a cross-rail, but are applicable to any tool slide or tool-carrying head regardless of its position or location.

It is believed that the foregoing conveys a clear understanding of the objects prefaced above, and while I have illustrated but a single working embodiment, it should be understood that various changes might be made in the construction and arrangement without departing from the spirit and scope of the invention as expressed in the claims.

I claim:

1. Feed mechanism of the character described, comprising, in combination, a feed screw, a gear having means for connecting it to the feed screw for revolving the latter, a feed shaft concentric with said gear and equipped with a disk arranged to turn with said shaft, means for imparting uniform oscillatory movement to the feed shaft, means operative between the disk and gear for transmitting variable oscillatory feed movement from the former to the latter and comprising a second disk concentric and relatively adjustable with respect to the first disk and feed shaft and having a stop member arranged to be set by such adjustment to vary the feed movement, a stop member on the first disk, and a part on the gear disposed between and arranged to be operated by said stop members for transmitting feed movement, means for imparting rapid traverse movement to the same gear, and means for optionally putting into operation said rapid traverse and feed movement means.

2. Feed mechanism as set forth in claim 1, in which the means for imparting oscillatory movement to the feed shaft operates through the agency of a clutch, and including means also operating through a clutch for imparting rapid traverse movement to the said gear, and a single control for said clutches.

3. Feed mechanism of the character described, comprising in combination a rack and means for reciprocating it, a pinion meshing with the rack, a feed shaft equipped with a fixed disk, a clutch for connecting the feed shaft to said pinion, whereby said shaft and its disk will be oscillated by reciprocation of the rack, a gear loose on the feed shaft, a feed screw adapted to be revolved by said gear, and means operative between said disk and gear for transmitting variable feed movement to the feed screw, including means for imparting rapid traverse movement to said gear when said clutch is disengaged.

4. Feed mechanism of the character de-

scribed, comprising in combination, a feed screw, a gear adapted for imparting rotative movement to said screw, a rapid traverse gear meshing with said gear for transmitting rapid traverse movement to the feed screw, a disk concentric with the first mentioned gear and having a peripheral projection, means for imparting uniform oscillatory movement to said disk, a disk concentric with and relatively adjustable on the first mentioned disk and having a projection, said projections constituting opposed abutments, and a part on the first mentioned gear located intermediate said projections and adapted to be operated thereby.

5. Feed mechanism as set forth in claim 4, in which the connection between the feed screw and the first mentioned gear includes a clutch adapted to be set for transmitting rotative movement in either direction to the feed screw.

6. Feed mechanism of the character described comprising a feed screw, a gear revoluble about the feed screw for turning it, a rapid traverse gear, a feed gear intermediate and in mesh with said gears, a feed shaft concentric with said feed gear, means for imparting rotative feed movement to said shaft, and means operative between said shaft and feed gear for transmitting feed movement to the latter including an adjustable means for producing lost motion for varying the degree of feed movement transmitted to said feed gear.

7. Feed mechanism of the character described, comprising a feed screw, a feed gear for turning the same, a feed shaft concentric with the feed gear, a pair of relatively adjustable drive transmitting parts on the feed shaft, a part on the feed gear located intermediate said drive transmitting parts and adapted to be moved by the latter for oscillating the feed gear variable degrees according to the adjustment of said parts, a rapid traverse gear, and means whereby relative movement will be imparted to said feed gear either from said feed shaft through the intermediary of said adjustable parts or from said rapid traverse gear.

8. In a machine tool of the character described, the combination of a driven shaft arranged to be driven continuously in either direction, an oscillating driven shaft, a feed screw, an operating gear adapted to impart rotative movement to said screw, independent gear connections between each of said shafts and said feed screw, through said last mentioned operating gear, each of said gear connections including a shiftable clutch, a reversible pawl and ratchet mechanism for driving the feed screw from said operating gear in either direction from the oscillating driven shaft in step by step feed impulses, said mechanism serving to drive the feed

screw continuously in one direction when operated from the continuously driven shaft through said operating gear, and a single manually shiftable clutch operating lever 5 for optionally engaging either of the two clutches to connect either the oscillating or the continuously driven shaft with the feed screw.

9. In a machine tool as set forth in claim 10 8, the provision of a reciprocatory rack hav-

ing a uniform stroke, a gear meshing therewith to communicate oscillatory movement to the oscillating driven shaft, and means including a variable lost motion driving connection between said oscillating driven shaft and said gear for operating said feed screw whereby to vary the rate of step by step feed substantially as and for the purpose described. 15

HARRY B. NEWTON.
